CASKET SHIPPING COVER

Richard V. Brady, 3608 County Club Drive,
Long Beach, Calif. 90807

Filed June 17, 1971, Ser. No. 154,264

Term of patent 14 years

Int. Cl. D31

U.S. Cl. D19—1

FIG.1

FIG.4

FIG. 1 is an end, top and side perspective view of a casket shipping cover, showing my new design in assembled position with the straps fastened;

FIG. 2 is an exploded opposite end, top and opposite side perspective view with the straps unfastened;

FIG. 3 is a top plan view in assembled position with the straps fastened;

FIG. 4 is a side elevational view in assembled position with the straps fastened, the opposite side being substantially a mirror image thereof; and

FIG. 5 is an end elevational view in assembled position with the straps fastened, the opposite end being substantially a mirror image thereof.

I claim:

The ornamental design for a casket shipping cover, substantially as shown and described.
